UNITED STATES PATENT OFFICE.

HOMER L. HULLINGER, OF CLEVELAND, OHIO.

DESIGN FOR A SIGNAL DEVICE.

47,425.

Specification for Design.

Patented June 8, 1915.

Application filed February 12, 1915. Serial No. 7,899. Term of patent 14 years.

To all whom it may concern:

Be it known that I, HOMER L. HULLINGER, a citizen of the United States, residing at Cleveland, county of Cuyahoga, and State of Ohio, have invented a new, original, and ornamental Design for a Signal Device, of which—

Figure 1 is a perspective view, and Fig. 2 a plan view, showing my new design.

I claim:

The ornamental design for a signal device as shown.

HOMER L. HULLINGER.

Witnesses:

R. B. MOSER,
M. SELIWAN.
